UNITED STATES PATENT OFFICE.

HERMAN PRIES AND JOHN W. MEYER, OF MICHIGAN CITY, INDIANA.

CAR-DOOR FASTENER.

SPECIFICATION forming part of Letters Patent No. 660,656, dated October 30, 1900.

Application filed July 20, 1899. Serial No. 724,460. (No model.)

To all whom it may concern:

Be it known that we, HERMAN PRIES and JOHN W. MEYER, citizens of the United States, and residents of Michigan City, county of La Porte, and State of Indiana, have invented 5 certain new and useful Improvements in Car-Door Fasteners, of which the following is a specification and which are illustrated in the accompanying drawings, forming a part 10 thereof.

This invention relates particularly to that class of car-door fasteners adapted to be secured by means of a seal which will prevent the opening of the door without detection. 15 Its object is to provide means for preventing the removal without breaking the seal of that part of the locking device which is secured to the car-body and with which the member secured to the door engages. This object is accomplished 20 in the construction hereinafter fully described, and which is illustrated in the accompanying drawings, in which—

Figure 1 is a detail plan section of a car body and door, showing a plan view of the 25 door-fastener. Fig. 2 is a detail side elevation of a car-body, showing full elevation of the fastener; and Fig. 3 is a detail section on the line 3 3 of Fig. 2.

We show at A a portion of the side of a car, 30 at a a part of the door-frame, and at B a portion of the door.

The fastening comprises a hasp C in hook form, having a lateral tongue-piece c and being secured to the door by means of a suitable 35 staple D. It comprises, further, a plate E, secured to the door-frame and to the body of the car, having a rearwardly-projecting tail-piece e for the latter purpose and being provided with an upwardly-extending wing F, 40 having a horizontal flange f, provided with a vertical socket to receive the tongue c of the hasp, and a vertical flange f'. The member E projects forwardly beyond the edge of the door-frame a, and this projection is curved

outwardly, as shown at e', forming a guide 45 for receiving the edge of the door and forcing it inwardly against the side of the car. The vertical flange f' is provided with a horizontal aperture G, and the tongue c is provided with a lateral aperture H, which when the 50 tongue is within the socket of the flange f is in alinement with the aperture G, so that the strap of the seal (not shown) may be passed through both of these apertures, tying the members c and f' together, thereby effectually 55 preventing the manipulation of the strap of the seal to permit the withdrawal of the hasp-tongue. The wing F is provided with an upward extension K, which forms a wear-plate for the body of the hasp. The staple D may 60 be of any desired form. We show it as having one of its arms attached to a plate d, through which a bolt may be passed, as shown, its other arm entering a short distance into the wood. 65

While we have shown the fixed member of the door-fastening as having its socketed portion projecting above its body portion, it is obvious that it may be variously designed without departing from the scope of the invention. 70

We claim as our invention—

In a car-door fastening, in combination, a hasp in hook form adapted to be attached to the door and having its hook transversely 75 apertured, a plate adapted to be attached to the door-frame, and having an upwardly-projecting wing having a horizontal and a perpendicular transversely-apertured flange, such wing having a bolt-hole above its horizontal flange, whereby it may be secured to the car-body by a bolt covered by the hook of the hasp when the door is fastened. 80

HERMAN PRIES.

JOHN W. MEYER.
